Inventor

Amos F. Morey.

By his Attorney Chas. H. Foster

UNITED STATES PATENT OFFICE.

AMOS F. MOREY, OF ASHLAND, KANSAS.

CHURN.

SPECIFICATION forming part of Letters Patent No. 356,694, dated January 25, 1887.

Application filed August 31, 1886. Serial No. 212,336. (No model.)

To all whom it may concern:

Be it known that I, AMOS F. MOREY, a citizen of the United States, residing at Ashland, in the county of Clarke and State of Kansas, have invented certain new and useful Improvements in Churns; and I do hereby declare that the following is a full, clear, and exact description of the same, reference being had to the annexed drawings, making a part of this specification, and to the letters and figures of reference marked thereon.

Figure 1 of the drawings is a sectional elevation of my improved churn; Fig. 2, a detail view in perspective of the lower end of the dasher-shaft with the dasher-blades removed, and Fig. 3 a similar view with the dasher-blades connected thereto.

The present invention has relation to that class of churning provided with what is termed a "compound dasher-shaft," wherein the upper end of the shaft enters a sleeve in which is located a spiral spring, said sleeve being connected to the driving mechanism and the shaft rotated with the sleeve by a coupling between the two, consisting of pins projecting laterally from the shaft and passing through elongated slots in the sleeve.

The objection to the above construction was the necessity of removing the pin before the dasher-shaft could be uncoupled when it was desired to remove the dasher-shaft from the churn-cylinder.

It is the object of my invention to improve the construction of the above class of dasher-shafts, whereby the same can be removed from the churn-cylinder without the necessity of removing the coupling-pins, thereby avoiding the danger of the pins being lost or mislaid; and a further object of the invention is to improve the construction of the dasher-head and blades, as will be hereinafter described, and subsequently pointed out in the claims.

In the accompanying drawings, the frame consists of suitable standards, A, which support the top B, said top and standards constituting the frame of the machine. The frame of the machine, however, may be of any desirable form or construction which may be found best adapted to the purpose, the top B having brackets a for supporting the shaft b, to which is connected the driving gear-wheel C,

said shaft having a suitable handle, e, for turning it. The teeth of the gear-wheel C mesh with those of a pinion, d, said pinion being connected to a short shaft, which has its upper end journaled in the top B of the frame in any suitable manner. The lower end of this shaft e is formed with a socket, f, and an annular flange, g, whereby the shaft is supported by means of the bracket h. The socket f is square or of irregular shape on its interior to correspond with the shape of the upper end of a rod, D, to prevent it from turning independent of the shaft e, and to be carried with it when said shaft revolves. This rod D has laterally-extending pins i, which project through elongated slots k in the hollow dasher-shaft E, said shaft extending through the cover F of the churn-cylinder G, and has located within it a spiral spring, H, which supports the lower end of the rod D.

The lower end of the dasher-shaft E is provided with a head, I, said head being concave on its four sides, as shown at l, and has curved mortises m, for attaching thereto the curved dasher-blades K, of either metal or wood.

The peculiar shape of the dasher-blades form buckets to lift the cream from the bottom of the churn and keep it continually agitated against the upper and inner sides of the churn-cylinder.

When the cylinder has been supplied with cream, the shaft b is turned by means of the handle c, carrying with it the large gear-wheel C, which, meshing with the teeth of the pinion d, will turn the short shaft e and carry with it the rod D, and by means of the pins i extending through the slots k the hollow dasher-shaft E will be turned with it.

The spring H allows the hollow shaft E to yield in a vertical direction to a slight degree and at the same time keeps the lower end of the dasher-head I engaged with the stationary pivot n on the bottom of the churn-cylinder.

When it is desired to remove the dasher-shaft, it is not necessary to remove the coupling-pins i, but by simply pressing down the rod D by means of the pin until the upper end of the shaft is disengaged from the socket f the dasher-shaft with the rod may be lifted out of the churn-cylinder.

The standards A are of iron, enabling the

frame to be placed in a tub of cool or warm water to temper the cream in the churn-cylinder, the entire exterior surface thereof coming in contact with the water.

5 Having now fully described my invention, what I claim as new, and desire to secure by Letters Patent, is—

1. In a churn, the combination, with a dasher-shaft provided with a head having its sides 10 concave and formed with vertical mortises, of concavo-convex dasher-blades seated in said mortises, suitably attached thereto and flush with the parallel face of the dasher-head, substantially as and for the purpose set forth.

15 2. In a churn, a driving gear-wheel and a pinion engaging therewith and irregular-

shaped socket formed on the pinion and having an annular bearing-flange by which it is supported in operative position by a bracket, in combination with a hollow and slotted 20 dasher-shaft, a coiled spring located therein, and a rod engaging with the shaft and socket and provided with pins extending through slots in the shaft, substantially as and for the purpose specified.

25 In testimony that I claim the above I have hereunto subscribed my name in the presence of two witnesses.

AMOS F. MOREY.
